United States Patent Office

Des. 226,544
Patented Mar. 27, 1973

226,544

CAP

Nicholas Veltri, 1183 Elmwood Ave.,
Buffalo, N.Y. 14202

Filed Nov. 11, 1971, Ser. No. 198,078

Term of patent 14 years

Int. Cl. D2—03

U.S. Cl. D2—247

FIG. 1.

FIG. 2

FIG. 1 is a perspective view of a cap showing my new design, taken from the front left quarter thereof; and FIG. 2 is a perspective view of the same taken from the right rear quarter.

I claim:

The ornamental design for a cap, substantially as shown.
